UNITED STATES PATENT OFFICE.

GEORGE E. STEVENS, OF LACONIA, NEW HAMPSHIRE.

KNITTING-MACHINE.

1,248,745.

Specification of Letters Patent.

Patented Dec. 4, 1917.

Application filed March 12, 1917. Serial No. 154,083.

To all whom it may concern:

Be it known that I, GEORGE E. STEVENS, a citizen of the United States, residing at Laconia, county of Belknap, State of New Hampshire, have invented an Improvement 5 in Knitting-Machines, of which the following description, in connection with the accompanying drawing, is a specification, like characters on the drawing representing like 10 parts.

This invention relates to dial knitting machines and has for its object to provide a novel attachment for such machines by which a slack course or courses can be formed in 15 the tubular fabric at predetermined intervals along the length thereof. Such slack courses are formed for the purpose of providing division lines in the fabric along which it may be cut to divide it into short lengths adapted 20 for tops of half hose, cuffs of shirts, drawers, etc. The device herein illustrated is somewhat similar to that illustrated in my co-pending application Se. No. 866,215, filed October 12, 1914. In said co-pending application, I have illustrated a construction 25 wherein the cam ring by which the vertical needles are actuated has a lever pivoted thereon carrying a roll situated directly beneath the outer ends of the horizontal needles and wherein pattern mechanism or a cam device is provided for raising the lever 30 at the time the slack course is to be formed thereby bringing the roll against the underside of the horizontal needles and elevating 35 the latter.

The cam mechanism for operating the vertical needles is also so constructed that when the slack course is to be formed the vertical needles are given an extra downward movement, such extra movement occurring simultaneously with the lifting of the horizontal needles. In the device illustrated in my 40 said co-pending application, the roll which acts on the horizontal needles is so constructed 45 that when it is raised into operative position, it will have contact with and elevate several needles at the same time. When the yarn which is being used is very fine and delicate, this operation of elevating several 50 needles at the same time is apt to place an undue strain upon the yarn.

The object of my present invention is to provide a novel slack course attachment of the above type which is constructed so that 55 one only or only two or three horizontal needles will be lifted at one time. In this way,

the strain on the yarn is greatly reduced and there will be less liability that delicate yarn will become broken in the slack course than where a considerable number of the horizontal 60 needles are lifted simultaneously.

In order to give an understanding of my invention, I have illustrated in the drawings a selected embodiment thereof which will now be described, after which the novel 65 features will be pointed out in the appended claims.

In the drawings, Figure 1 is a side elevation of a portion of a knitting machine having my improvements applied thereto; 70

Fig. 2 is a partial sectional view on the line 2—2, Fig. 1;

Figs. 3 and 4 are detail views through the dial-needle-elevating-member taken on substantially the line 3—3, Fig. 1, said views 75 illustrating the operation of lifting the dial needles;

Fig. 5 is a view of the dial-needle-elevating member;

Fig. 6 is a section on the line 6—6, Fig. 5. 80

The dial knitting machine illustrated in the drawings comprises the frame or bed 1 carrying a needle cylinder 2 in which the vertical or cylinder needles operate, as usual, and also carrying the circular dial 3 in 85 which the dial needles 40 operate.

The vertical or cylinder needles are given their vertical or knitting movement by means of a cam carried by the cam ring 4 which is rotatably mounted on the frame, as usual 90 in dial-knitting machines, and the dial needles are given their knitting movement by means of a dial cam 5 which rotates with the cam ring 4, said dial cam being herein shown as secured to a yoke or frame 6 which 95 is rigid with the cam ring 4. The cam ring 4 is driven by any suitable or usual mechanism which, however, is not herein shown, as it forms no part of the present invention. The cam ring 4 has associated therewith a 100 movable cam member which is brought into play at the proper time to give the cylinder needles an extra downward movement for the formation of a slack course, this movable cam member being herein actuated by a lever 7 pivoted at 8 to the cam ring and provided with a pin 9 which is adapted to be actuated by a pattern cam 10 mounted on a rotary shaft 11 extending from the cam ring. This shaft is actuated to bring 105 the cam 10 into operation periodically by means of a star wheel 12 mounted thereon 110

which at each rotation of the cam ring is engaged by one or more pins carried by the frame 1. The cam ring 4 is shown as having a bracket 16 secured thereto to which one end of a lever 14 is pivotally connected, as at 15. This lever 14 carries a needle-lifting member 13 that is adapted to engage and lift the dial needles at the time the slack course is to be formed. The outer end 10 of the lever 14 has a screw 17 screw-threaded therethrough, said screw being situated to be engaged by the pin 9 so that when the lever 7 is raised thereby to cause the vertical needles to have their extra downward movement, the lever 14 is also raised, thus bringing the needle-lifting member 13 into engagement with the dial needles and raising them.

The needle-lifting member 13 is constructed so that it can be made to act on one dial needle 40 only at a time, or on two or three or more needles at the same time as desired. This needle-lifting member is provided with the beveled surface 20 which is situated parallel to the dial needles 40. The edge of the needle-lifting member 13 is provided with a notch 21 shaped to present a square shoulder 22 at the edge of the beveled surface 20. The lever 14 is bent so that the portion thereof to which the needle-lifting member 13 is secured stands at an inclination, and the needle-lifting member 13 is adjustably secured to the lever by means of a screw 24. If the screw is loosened, then the needle-lifting member can be adjusted about the screw as a pivot so as to change the angular position of the shoulder 22. This needle-lifting member may be adjusted with the shoulder 22 in such position that 40 when the lever 14 is raised, one needle 40 only will be engaged by the beveled portion 20, the other needles occupying the recess or notch 21. If, however, the needle-lifting member 13 is adjusted into the position 45 shown in Fig. 6, then the beveled surface 20 is so positioned that when the needle-lifting member is raised, it will have engagement with two or more of the needles 40, thus elevating this number of needles simultaneously. The provision of the notch 21 with the shoulder 22 and the adjustment of the needle-lifting member about its pivotal screw 24 provides means whereby the needle-lifting member may be made to act on one 50 needle only at a time or on a plurality of needles. It will be seen that the needle-lifting member is frusto-conical in shape so that the beveled surface 20 has a conical shape. The advantage of this is that as the

needle-lifting member is carried around underneath the dial needles by the cam ring 4, the beveled surface 20 will have a camming action against the needles 4, thus raising them gradually. As each needle passes over the shoulder 22, it will drop off from 65 the shoulder and resume its normal position. The device has the advantage, however, that it can be adjusted to operate on one or more needles at a time.

I claim:

1. In a knitting machine, the combination with cylinder needles, of a rotary cam ring for operating them, dial needles, means for actuating said dial needles, a lever pivoted at one end to the cam ring, a needle-lifting member carried by the lever intermediate of its ends, a pattern-actuated lever also pivoted to the cam ring, and connections between said pattern-actuated lever and the first-named lever whereby the latter is raised 80 by the former thereby to bring the needle-lifting member into engagement with the dial needles, said needle-lifting member being adjustable on its supporting lever and constructed to lift one or more needles at 85 each operation thereof, depending upon its adjustment.

2. In a knitting machine, the combination with cylinder needles, of a rotary cam ring for operating them, dial needles, means for actuating said dial needles, a lever pivoted at one end to the cam ring, pattern-actuated mechanism for raising the lever, and a needle-lifting member adjustably carried by 90 said lever and adapted to engage and raise 95 the dial needles when the lever is lifted, said needle-lifting member being constructed to contact with a different number of needles in different adjusted positions.

3. In a knitting machine, the combination with cylinder needles, of a rotary cam ring for operating them, dial needles, means for actuating said dial needles, a lever pivoted at one end to the cam ring, pattern-actuated mechanism to raise the lever at predetermined times, and a needle-lifting member adjustably mounted on the lever and adapted to be brought into engagement with the dial needles when said lever is raised, said needle-lifting member having a needle-engaging 100 surface and a notch adjacent said surface whereby the adjustment of said needle-lifting member on the lever will position it to engage a greater or less number of needles.

In testimony whereof, I have signed my 115 name to this specification.

GEORGE E. STEVENS.
